SEAM PRESSING MACHINE

Edward Quinn, Saugus, and Fred E. Muzzey, Haverhill, Mass., assignors to United Shoe Machinery Corporation, Flemington, N. J., a corporation of New Jersey

Application July 20, 1944, Serial No. 545,798

9 Claims. (Cl. 69—7)

2

1 This invention relates to machines for pressing seams in shoe parts and is herein disclosed as embodied in a machine of the type illustrated and described in an application for United States Letters Patent Serial No. 544,728, filed on July 13, 1944, in the name of Milton H. Roske. That application discloses and claims a seam pressing machine having provision for tensioning a work piece transversely during the performance of the operation and a divisional application filed thereunder on September 22, 1945, Serial No. 618,004, discloses and claims the method of thus tensioning the work piece. The machine illustrated herein, like that disclosed in the Roske applications, is provided with a seam pressing roll of relatively large diameter and with a pair of work feeding and tensioning rolls between which the pressing roll extends. Suitable supports are provided in both machines for holding the work against the pressing roll and the feed rolls.

It is an object of the present invention to provide an improved seam pressing machine of the type under consideration. In accordance with this object, a feature of the invention consists in a novel arrangement of the feeding mechanism wherein the feed rolls are not only carried by separate shafts, but are also arranged in coaxial relation to each other. Compression springs surrounding the shafts are provided for urging the feed rolls toward each other against the work piece. The feed rolls have frusto-conical peripheries which cooperate with the work support not only to control the feed of the work piece, but to tension the work piece over the support. Such tensioning has been found to result in better work.

Another feature of the invention consists in the provision of a supporting member having work-engaging portions of different contour (grooved and non-grooved) which may be selectively brought into operating position to meet the demands of the particular job.

These and other features of the invention, including certain details of construction and combinations of parts, will be described in connection with an illustrative machine and pointed out in the appended claims.

Referring now to the accompanying drawings, Fig. 1 is a view in side elevation of an illustrative machine embodying the invention;

Fig. 2 is a front view of the machine, looking down at an angle corresponding to the tilt of the frame as shown in Fig. 1;

Fig. 3 is a large scale side elevation of the

work-engaging instrumentalities in operation upon a work piece;

Fig. 4 is a front view of the parts shown in Fig. 3;

Fig. 5 is a section taken on the line V—V of Fig. 3;

Fig. 6 is a section taken on the line VI—VI of Fig. 3;

Fig. 7 is a view similar to Fig. 6, omitting the feed rolls and showing the presser roll in a different position of rotation; and

Fig. 8 is a detail view of a portion of the pressing roll.

The operating instrumentalities of the illustrative machine comprise a driven seam pressing or seam rubbing roll 10 of relatively large diameter, a work support 12, and a pair of driven feed rolls 14 and 16. The work is guided to the operating members by a seam ridge guide 18 and a seam crease guide 20. The seam pressing roll, the feed rolls and the seam ridge guide are supported by a yoke-shaped bracket 22 (Fig. 1) having a crosspiece 24 and a pair of downwardly extending arms 26 and 28 which are positioned on opposite sides of the work support 12 and are secured at their lower ends to a crosspiece 30. The work support 12 is mounted on the crosspiece 30. For the convenience of the operator, the entire frame may be tilted back to the most desirable operating position. To this end, the crosspiece 30 is hinged upon a pintle or crosspin 34 which is clamped by setscrews 33 in holes formed in ears 35 extending rearwardly from the crosspiece 30. The ends of the pintle 34 are journaled in bearing holes formed in a pair of base brackets 36 having upwardly extending side plates 38. The brackets 36 are adapted to be secured to a work bench 39. The crosspiece 30 is clamped in the desired position of tilted adjustment by screws 40 (Fig. 1) extending through arcuate slots 42 in the side plates 38 and threaded into brackets 44 (Fig. 2) secured upon the arms 26 and 28.

The seam pressing roll 10 is a relatively narrow disk-like member having a fluted periphery. It is secured upon a shaft 46 journaled in bearings 48 carried by the arms 26 and 28 and also in bearings 50 carried by brackets 52 depending from the crosspiece 24. A pulley 54 on the shaft 46 is driven by a belt 56 which, in turn, may be driven from any suitable source of power. The roll 10 is thus driven at relatively high speed.

The feed roll 16 is secured upon one end of a shaft 58. A gear 60, secured to the opposite end of the shaft 58, meshes with a gear 62 on a shaft 64 parallel to the shaft 58. Secured upon the

shaft 64 and driven by a bevel gear 66 is a bevel gear 68. A hollow shaft 70 mounted for rotation on a stationary bearing pin 72 carries the bevel gear 66 and also a worm gear 74 which meshes with a worm 76. A shaft 78 which carries the worm 76 is driven through a pulley 82 from a belt 80 which, in turn, is driven from any suitable source of power. The shaft 58 is journaled near one of its ends in a bearing 88 carried by a yoke-shaped bracket 88 which is clamped at one end by screws 90 to the arm 28 and at the other end by screws 91 to the arm 26. The screws 90 and 91 are threaded into their respective arms and extend through slots formed in the bracket 88 to provide for forward and backward adjustment of the bracket, the slots being wide enough to permit some heightwise adjustment also. The shaft 58 is journaled near its other end in a bearing 84 carried by a bracket 93 secured to and extending forwardly from the bracket 88. Surrounding the shaft 58 is a coil compression spring 92 one end of which bears against a washer 94 which, in turn, is supported against the thrust of the spring by the bearing 86. The opposite end of the spring 92 bears against a collar 96 which is secured by a setscrew 98 to the shaft 58. The bearings 86 and 84 permit the shaft 58 not only to turn freely, but also to slide in the direction of its axis. The extent of this sliding movement is so slight as to render the relative displacement of the gears 60 and 62 negligible. Movement of the shaft 58 to the left, as viewed in Fig. 2, under the influence of the spring 92 is limited by a collar 100 secured upon the shaft by a setscrew 102 and engaging the bearing 84. The shaft 64 is journaled in suitable bearings 104 secured in the bracket 88, and the shaft 78 is mounted in suitable bearings 101 and 103 carried by brackets 105 and 107 secured to the bracket 88. The bearing pin 72, which has a reduced threaded end 115 and also a collar 109 bearing against a finished annular surface on the gear 74, is clamped by a nut 111 to a bracket 113 secured to the bracket 88.

The feed roll 14 is secured upon the right-hand end of a shaft 106 which is mounted in bearings 108 and 110 carried by the bracket 88 and a bracket 112, respectively, the bracket 112 being mounted on the bracket 88. The shaft 106 is driven by a gear 114 upon one of its ends, and the gear 114, in turn, is driven by a gear 115 (Fig. 2) mounted upon the shaft 64. The feed roll 14 is urged toward the right by a compression spring 116 in the same manner as the feed roll 16. The arrangement of the feed roll 14 is in all respects similar to that of the feed roll 16 except that the feed roll 14 is mounted upon the right-hand end of the shaft 106 and is urged toward the right. The feed rolls 14 and 16 have frusto-conical knurled or lightly roughened working surfaces 118 (Fig. 6).

The arms 28 and 26 are cut away in the vicinity of the bearings 86 and 108 to accommodate the forward and backward, and also heightwise, adjustments of the bracket 88 already mentioned.

The seam ridge guide 18 consists of a pair of spaced members 120 and 122 (Figs. 3, 4 and 5) which engage opposite sides of the seam ridge. The guide member 120 is mounted on a block 121 (Fig. 4) which is carried upon the lower end of a slide 124 and the guide member 122 is mounted on a block 123 which is carried upon the lower end of a slide 126. Each of the blocks 121 and 123 (Figs. 3 and 4) has a tongue 125 which is T-shaped in cross section and which is horizon-

tally slidable in a complementary groove in its respective slide 124 or 126. A screw 127, oppositely threaded through the blocks 121 and 123, may be turned in one direction or the other to adjust the blocks closer to or farther from each other. Each of the blocks 121 and 123 has also a tongue-and-groove connection with its respective guide member 120 and 122 to provide for heightwise adjustment of the guide member. The guide members 120 and 122 are secured to their respective slides by screws 140 which extend through slots in the slides to provide for individual heightwise adjustment of the slides.

Both guide members 120 and 122 taper rearwardly from their supporting slides to a point close to the pressing roll 10, as shown in Fig. 3. The work-engaging surfaces of these guides, in cross section, an open or truncated inverted V, as shown in Fig. 5. The slides 124 and 126 are connected by a crosspiece 128 (Figs. 1 and 2) and move as a unit. They are slidable heightwise in guideways 130, the principal portions of which are integral with and depend from a bracket 131 (Fig. 1) secured by screws 133 to the frame member 22 with provision for forward and rearward adjustment. A tension spring 132 having its upper end secured to the crosspiece 128 and its lower end secured to the frame 22 urges the guide members 120 and 122 downwardly as far as permitted by the shoulder of a stop screw 134 turning freely in a lug 136 extending rearwardly from the crosspiece 128, the screw 134 having its lower end threaded in a portion of the frame 22. Upward movement of the guide members to avoid any danger of their accidental engagement with the pressing roll 10 is limited by a stop 138 secured to the frame 22 and having its upper end hooked over the crosspiece 128.

The work support consists of a central disk 142, which supports the work against the pressure of the roll 10, and a pair of side disks 144 and 146 which support the work against the pressure of the feed rolls 14 and 16, respectively. The disk 142 has a hub 143 which is mounted upon a shaft 150 supported between a pair of spaced ears 152 carried by a plunger 154 (Fig. 1). The disks 144 and 146 are of the same diameter as the disk 142 and they have beveled peripheral portions 156 extending close to the periphery of the disk 142. The work engaging portions of the disks 144 and 146, while smooth to avoid marring the visible surface of the work piece, nevertheless develop some friction against the work piece. The disks 144 and 146, however, are mounted on ball bearings (not shown) and are freely rotatable upon the hub 143 and thus cooperate with the feed rolls 14 and 16 to advance the work with a minimum of drag. The plunger 154 is movable heightwise in a guideway formed in a bracket 158 (Fig. 1) having an integral base 160 which is secured to a block 162 mounted on the crosspiece 30. Clamping screws 164 threaded into the block 162 extend through slots in the base 160 to enable the bracket 158 to be adjusted forwardly and rearwardly.

The plunger 154 is urged upwardly by a spring 166 (Fig. 1) housed in a bore in the plunger. The lower end of the spring 166 bears against the upper end of a smooth shank formed on an adjusting screw 168 threaded into the base 160 and having a knurled head 170 by which it can be turned to adjust the compression of the spring 166. The lower end of the screw 168 extends into a recess 171 in the block 162. Upward movement of the work support under the influence

of the spring 166 is limited by a stop 172 (Fig. 1) having its upper end hooked over a projection extending from the base of the ears 152. The stop 172 is clamped to the bracket 158 by a screw 174 threaded into the bracket and passing through a slot formed in the stop to permit heightwise adjustment. Fine adjustment of the stop 172 is facilitated by a screw 176 threaded into a lug 178 extending from the bracket 158. The screw 176 passes loosely through a lug 179 on the stop 172 and has a head 180 which bears against the lug 179.

The seam crease guide 20 is an upstanding blade-like member mounted upon a bracket 182 which is clamped by the screw 174 against the stop 172. The lower end of the bracket 182 has a slot to accommodate the screw 174 for various positions of heightwise adjustment of the seam crease guide 20. It will be noted that the seam crease guide 20 is supported independently of the plunger 154 and that it does not partake of the heightwise yielding movement of the work supporting rolls. Its position is therefore fixed (subject to adjustment) in relation to the pressing roll 10.

For flat work such as quarter side seams and lining side seams the working surface of the supporting disk 142 should be cylindrical (i. e., flat in radial section), as shown in Fig. 5, while for curved work such as backseams it should be grooved, as shown in Figs. 6 and 7. The purpose of the groove is to enable the pressing roll not merely to flatten the seam, but to displace the surplus material of the seam into the groove and thus mold the seam into the general curvature of the back part of the shoe upper. When the work piece, which is inside out during the operation, is turned right side out, the displaced seam material will fill the space at the backseam and thus prevent the formation of a sharp crease, as seen from the outside. For simplicity of disclosure, the disk 142 has been shown with only one grooved portion; but it may be desirable to provide (at different portions of the periphery) several grooves of different widths to accommodate different thicknesses of material. A relatively narrow groove, less than the full width of the periphery of the disk 142, would be used for thin material and a wider groove for thick material. In the illustrated machine both forms of periphery (grooved and non-grooved) are provided on the same disk 142, and the desired form is brought into operative position by loosening a setscrew 184 threaded through one of the ears 152, rotating the disk 142 to bring the selected portion of its periphery into operative position, and then clamping the disk against rotation by tightening the setscrew 184.

In order to stiffen the seam crease guide 20 against lateral displacement, slots 186 (Fig. 3) are formed in the periphery of the work supporting disk 142 to receive the tip of the seam crease guide. The slots 186 are so positioned that one or the other will register with the tip of the seam crease guide when the disk 142 is rotated to bring a selected portion of its periphery (i. e., flat or grooved) into operative position.

The pressing roll 10 (Fig. 8) may, if desired, be fluted sharply enough to form cutting edges which serve to remove some of the material of the seam ridge. The portions of the periphery immediately following these edges are not backed away from the edges; they bear against the work to flatten the material which has not been removed. The fluting may be formed in such a

way as to leave a set of sharp edges 188 for one direction of rotation and a set of rounded projecting surfaces 190 for the opposite direction, the roll being reversible upon its shaft to enable either set to become operative without reversing the direction of drive in a machine of the type disclosed herein.

In the operation of the machine a work piece W consisting of a pair of back quarters of a shoe upper united by a seam which forms a ridge R is fed by hand with the seam ridge entering the V-shaped notch between the guides 120 and 122 and with the seam crease riding upon the guide 20. The feed rolls 14 and 16 engage the work piece on opposite sides of the seam and press the work piece against the freely rotatable disks 144 and 146. The feed rolls advance the work piece until the leading end of the work piece comes into contact with the pressing roll 10; then they control the feed of the work piece by holding it back against the tendency of the rapidly rotating pressing roll to eject it from the machine, permitting the work piece to feed at the rate imposed by the feed rolls. Another function of the feed rolls is to tension the work piece over the work support. Such tensioning serves to pull the work piece down on opposite sides of the work support at the locality of operation. Now the radius of the work support (i. e., the equal radii of the disks 142, 144 and 146) is less than the radius of heightwise curvature of the backseam of a shoe. To pull the work piece downwardly on opposite sides of the work support will not therefore tend to strain the stitches or straighten out the heightwise curvature of the backseam, while to pull the work piece directly across the seam and not downwardly upon a work support might produce these undesirable results.

As the taut work piece thus advances under the control of the seam ridge guide 18 and the seam crease guide 20, the ridge R is rubbed down substantially flat by the rapidly rotating fluted roll 10. The work supporting disk 142 may yield downwardly in opposition to the spring 166 as occasioned by variations in the thickness of the work piece and the feed rolls may yield laterally in opposition to their springs 92 and 116, likewise to accommodate variations in the thickness of the work piece. The pressing roll 10, because of its large diameter and rapid speed, can perform its operation with a minimum of pressure against the work (by the spring 166) and without damage to the stitches of the seam.

The tension of the work piece may be increased by a lowering of the feed rolls 14 and 16 through a downward adjustment of the bracket 88, or by a tightening of the springs 92 and 116. The locality of greatest tension may be shifted forwardly or rearwardly by a corresponding adjustment of the bracket 88. The adjustment of the bracket 88 to obtain the desired position of the feed rolls is made when the machine is being assembled, and in the absence of unusual circumstances, it need never be changed.

Having described my invention, what we claim as new and desire to secure by Letters Patent of the United States is:

1. In a seam pressing machine, a work support, a seam rubbing tool, a pair of coaxial driven feed rolls on opposite sides of said work support and of said tool, said feed rolls having frustoconical work engaging surfaces which flank the seam rubbing tool, and resilient means for press-
70 ing said feed rolls toward each other to cause

them to grip the work against the sides of the work support.

2. A seam pressing machine comprising a work support, a seam rubbing roll of relatively large diameter, a pair of coaxial shafts having a space between their adjacent ends, a feed roll mounted on each of said shafts, said shafts and said feed rolls being arranged for axial movement of the feed rolls, said feed rolls having frusto-conical work engaging surfaces, and springs for pressing said feed rolls toward each other to cause them to grip the work against the sides of the work support, the seam rubbing roll extending into the space between the ends of the shafts to bring the locality of operation of the large diameter seam rubbing roll close to the locality at which the work is gripped between the feed rolls and the work support.

3. A seam pressing machine comprising a seam pressing tool, means including a pair of beveled rolls for supporting the seam of a work piece against the pressure of the seam pressing tool, said rolls being engageable with one surface of a work piece, means for supporting said rolls for free rotation independently of each other about a common axis, a pair of rolls co-operating individually with the rolls of the first-mentioned pair to feed the work piece and engageable with the opposite surface of the work piece, and means for driving the rolls of the second-mentioned pair.

4. In a seam pressing machine having a seam pressing tool and a work feeding means, a work support comprising a member engageable with the under surface of a work piece for supporting the seam of a work piece against the pressure of the seam pressing tool, and a pair of freely rotatable idler rolls at the opposite sides respectively of said supporting member and engageable with the under surface of the work piece for supporting the work piece against the pressure of the feeding means.

5. In a seam pressing machine having a seam pressing tool and a work feeding means, a work support comprising a member engageable with the under surface of a work piece for supporting the seam of a work piece against the pressure of the seam pressing tool, a pair of freely rotatable idler rolls at the opposite sides respectively of said supporting member and engageable with the under surface of the work piece for supporting the work piece against the pressure of the feeding means, and resilient means for urging said work supporting member and said idler rolls upwardly as a unit to a stop position from which they may yield downwardly as occasioned by the thickness of the work.

6. In a seam pressing machine, a work support comprising a member for supporting the seam of a work piece against the pressure of a seam pressing tool, beveled coaxial disks, one on each side

of the work support, and means for supporting said disks for free rotation independently of each other about their common axis, said disks having their peripheries closely adjacent to and substantially continuous with the work support at the locality of operation.

7. A seam pressing machine comprising a seam pressing tool, a member for supporting the seam of a work piece against the pressure of the seam pressing tool, a pair of frusto-conical idler rolls at the opposite sides of the seam supporting member, and a pair of driven friction rolls co-operating with the idler rolls to advance the work.

8. In a seam pressing machine having a seam pressing tool and work feeding means, a work support comprising a rotary disk having various portions of its periphery of different contour in radial section, a pair of frusto-conical idler rolls at the opposite sides respectively of said disk, a holder in which said disk and said rolls are mounted for rotation about a common axis, and means for securing said disk against rotation after it has been turned to bring a selected portion of its periphery into operating position to support the work against the pressure of the seam pressing tool, said idler rolls serving to support the work against the pressure of the feeding means and being freely rotatable to facilitate the feed of the work.

9. A seam pressing machine comprising a seam pressing tool, a work support, resilient means urging said work support toward the seam pressing tool to hold a work piece yieldingly against the tool, a seam crease guide, and a rigid support for said seam crease guide which is independent of the resiliently urged work support for holding the seam crease guide in fixed relation to the seam pressing tool regardless of the yielding movement of the work support.
